UNITED STATES PATENT OFFICE.

FRANK GLASNER AND GEORGE ELLISON, OF HINTON, IOWA.

DRINKING-CUP.

1,227,423.

Specification of Letters Patent.

Patented May 22, 1917.

Application filed June 23, 1916. Serial No. 105,482.

To all whom it may concern:

Be it known that we, FRANK GLASNER and GEORGE ELLISON, citizens of the United States, residing at Hinton, in the county of

5 Plymouth and State of Iowa, have invented new and useful Improvements in Drinking-Cups, of which the following is a specification.

The present invention relates to an improvement in foldable sanitary drinking cups, and an object of the invention is to produce an article of this class which shall be extremely simple, cheap to manufacture, as well as ornamental and whereby the cup, 15 when not in use, will be effectively protected.

Another object of the invention is to produce a foldable drinking cup which may be folded or collapsed to such a size as 20 to be conveniently carried in the pocket of the user or which may be provided with a suitable cap and attached to the said pocket and occupy only a small space upon the clothing of the wearer.

25 A further object of the invention is to produce a collapsible drinking cup wherein the cup proper is constructed of some textile water-proof material and arranged in a suitable tube having means for projecting the same partly from one end of the tube, and when in such projected condition the textile body will automatically move to produce a substantially cone-shaped cup.

35 It is a still further object of the invention to produce a foldable cup of this character including a textile body having spring means for normally expanding the same to a cup-shape and which is adapted to be 40 partially folded within the tube when the cup is not in use and adapted, during the process of such folding, to be subjected to a wiping process to remove all moisture from the cup, and still further to provide 45 the same with a protective casing having means arranged thereon, in the nature of a cap, whereby the same may be effectively suspended from the pocket of the clothing of the user.

50 With the above and other objects in view the improvement resides in the construction, combination and arrangement of parts set forth in the following specification and falling within the scope of the appended 55 claims.

In the drawing:

Figure 1 is a perspective view of the improvement in its folded or collapsed position,

Fig. 2 is a perspective view showing the 60 arrangement of parts when the textile body is moved longitudinally of the tool to produce a drinking cup,

Fig. 3 is a top plan view of the same,

Fig. 4 is a view illustrating the arrangement of parts when the textile body has been moved inwardly of the tube to collapse the same, and previous to the turning of the body upon the tube to wring the same, and

70 Fig. 5 is a cross sectional view showing the body partially received within the tube, as when the protective sleeve is to be applied.

75 In carrying out our improvement we employ a tubular member 1 which is provided with three angularly disposed slits 2—2 which enter from one of the ends of the tube and which terminate a suitable distance from the other end. The tube is further provided diametrically opposite the central slit 2, with a slot or opening 3 extending through the entire length of the tube.

80 Within the tube 1 we position a slidable member 4 having a projecting stud 5 which is adapted to play through the slot or opening 3 in the tube. This member 4 is round in plan and is of a length so that the same will not be entirely withdrawn from the tube when moved in one direction. The 85

member 4 upon its inner face has secured thereto a pair of right angularly arranged substantially V-shaped springs 6 and 7 respectively and secured to the arms of these springs is the textile body of the cup 8. By sliding the member 4 longitudinally of the tube to project the textile body through one end of the said tube, it will be apparent that the arms of the springs 6 and 7 will expand and consequently move the textile body to 90 provide a cup which is approximately of a hollow frusto-pyramidal formation, as clearly shown in Fig. 2 of the drawing. It

95 will be noted that the slits 2 as well as the slot 3 are so arranged as to permit of portions of the textile body 8 being projected therethrough when the member 4 is moved to collapse the cup, and when the stud 5 of the said member 4 is brought out of the slot 3 the member 4 is adapted to be rotated 100

105

110

2

around the tube 1 so that the opposite edges of the slits as well as the slot 3 will engage with the projecting portions of the textile body and so rinse the moisture therefrom.

5 By reference to Fig. 4 it will be noted that portions of the body will lap upon the exterior of the tube 1, and when the device is in this position the protective sleeve 9 is arranged over the lapped edges of the textile

10 body and over the tube 1, this sleeve being slit to provide the same with a cap 10 which may be inserted over the edge of the pocket of the user.

While the body 8 has been described as of 15 a textile nature it is to be understood that the same is to be constructed of rubberized silk or any other suitable flexible waterproof material.

From the above description, taken in connection with the accompanying drawing, the simplicity of the device, as well as the advantages thereof will, it is thought, be perfectly apparent to those skilled in the art to which such invention appertains without 25 further detailed description.

Having thus described the invention, what we claim is:

1. In a device for the purpose set forth, a tube which is slit from one of its ends to 30 adjacent its other end and which is provided

with a slot extending longitudinally therethrough and disposed diametrically opposite one of the slits, a member within the tube having a stud normally arranged in the slot, substantially V-shaped springs arranged one 35 at a right angle to the other and connected at their central portions to the said member, and a textile body secured to the arms of the springs and to the movable member, all as and for the purpose set forth.

2. In a device for the purpose set forth, a slitted tube, a member movable within the tube, a textile body secured to the member, spring means connected with the member and with the body and adapted when the 45 movable member is slid longitudinally of the tube in one direction, to permit of the expansion of the springs and to bring the textile body to cup formation, the said body adapted to be received in the slits of the tube 50 when the movable member is moved in an opposite direction to bring the body within the tube, said movable member being rotatable upon the tube, and a protective sleeve 55 for the body and for the tube, and said sleeve having a spring clip.

In testimony whereof we affix our signatures.

FRANK GLASNER.
GEORGE ELLISON.
